HYDRANT.

Filed Oct. 19, 1925

R. W. PENNY
INVENTOR

BY ATTORNEY

UNITED STATES PATENT OFFICE.

ROY W. PENNY, OF RALEIGH, NORTH CAROLINA.

HYDRANT.

Application filed October 19, 1925. Serial No. 63,388.

My present invention relates to improvements in hydrants for use in supplying and distributing water for fire control systems and adapted especially for use in municipalities on streets or highways. The primary object of the invention is to improve hydrants now in use and utilizing a plurality of ports for the hydrant including a main port for connection with a power pumping engine, together with auxiliary ports which may be used before the power pumping engine is coupled with the hydrant. The auxiliary ports are under control of a rotary valve accessible for operation from the exterior of the hydrant. By constructing the hydrant according to the principles of my invention essential time may be saved in preparing to fight a fire by first utilizing the auxiliary ports to supply one or more streams of water while the connection is being made to the hydrant for the main hose line to the power pumping engine. Means are provided whereby the position of the ports of the rotary valve may readily be ascertained; means are provided for retaining the valve in adjusted position, and other meritorious features and accessories are embodied in the present invention as will hereinafter be set forth. The invention consists in certain novel combinations and arrangements of parts for the above indicated purposes as will be pointed out in my appended claims.

In the accompanying drawings I have illustrated one complete example of the physical embodiment of my invention wherein the parts are combined and arranged according to one mode I have thus far devised for the practical application of the principles of my invention.

Figure 1 is a vertical sectional view of the hydrant of my invention with some parts in elevation for convenience of illustration.

Figure 2 is a sectional view of the detached, rotary valve of the hydrant.

Figure 3 is a top plan view of the hydrant with some parts omitted.

Figure 4 is a transverse sectional view as at line 4—4 of Figure 1 with the elbow and other parts omitted for convenience of illustration.

Figure 5 is a sectional detail view showing the spring-pressed detent for the rotary valve.

55 In carrying out my invention I have

adopted a well known style or pattern of hydrant now in use, which is usually provided with an elbow or casting 1 located underground and connected with the water main. The hydrant as herein illustrated comprises 60 a shell or hollow casing made up in sections as 2 for the base, 3 the cylinder, and 4 the head of the hydrant. These sections are cast as separate members and they are provided with annular attaching flanges 5 and secured together with bolts 6 in suitable manner in order that access to the interior of the hydrant may readily be had when necessary and to assist in assembling the parts.

A main reciprocating valve 7 of usual type 70 is located in the lower part of the hydrant to control admission of water thereto from the water main, and this valve is normally closed as indicated in the drawings. The valve is vertically movable and co-operates 75 with a valve seat 8 from which it may be withdrawn through movement imparted to its stem 9 that projects upwardly into the hydrant. A non-rotary spider frame 10 is coupled or fixed on the stem and moves bodily with it to guide and stabilize the valve in its opening and closing movements as it is lowered or raised.

Above the reciprocating valve and fashioned in the cylinder section 3 is a main port 85 11 that is normally closed by a cap 12 having a nut portion 13 for the application thereto of a wrench when uncovering the port for connection of the main hose line of a pumping engine. This main port is unobstructed, except for the closure cap and after the reciprocating valve is opened water may be withdrawn through the applied hose line in usual manner.

In addition to the main port a plurality 95 of auxiliary ports 14 and 15 are provided in the cylinder 3, said ports preferably being located in the walls of the cylinder and spaced at an angle of 90° as indicated in Figure 4. These ports are normally closed 100 from the exterior by caps or closures 16 and 17 screwed on the threaded bosses of the ports in manner similar to the cap of the main port.

The auxiliary ports are controlled from 105 the interior of the hydrant by means of a hollow, rotary valve 18 which is fashioned with ports 19 and 20 adapted to register with the ports 14 and 15 respectively of the cylinder that encases the valve.

The rotary valve is preferably fashioned with an enlarged head 21 at its lower open end and bronze packing rings are used in the head to insure a water tight joint but permit rotation of the valve when required. At its upper end the hollow valve is fashioned with a flanged head 22 which is seated in an annular groove 22' provided therefor in the upper end of the cylinder 3 as a bearing for the valve. The valve stem 23 is shown as hollow and it is fashioned with a nut portion 24 exterior of the hydrant and an annular bearing flange 25 also exterior of the hydrant and adapted to frictionally engage the bearing face 26 on the reduced portion of the head 4 of the hydrant. By means of a suitable wrench applied to the nut 24 it will be apparent that the valve may be turned within its cylinder or cylindrical casing to regulate flow of water through both its ports 19 and 20 from the interior of the hydrant and through the complementary ports 14 and 15 of the cylinder or casing. Thus water under the regular main pressure may be obtained from the hydrant by use of either or both of the ports 14 and 15.

For indicating the position of the valve two pointers 27 and 27' are utilized on the flange 25 of the nut 24, which, as seen in Figure 3 point to the axial lines of the respective ports 14 and 15 or 19 and 20 when the pair of auxiliary ports are open, and are arranged in fixed relation to the valve ports for indicating their positions.

The main reciprocating valve 7 is also manipulated from the exterior of the hydrant, through an operating rod 28 alined with the valve stem 9 of the reciprocating valve. This rod is fashioned with a nut or head 28' exterior of the hydrant for use with a wrench, and at its lower end within the hollow rotary valve the rod is fashioned with an interiorly threaded head 29 that engages complementary threads on the upper end of the valve stem 9. The rod extends downward through the valve stem 23 and the head 29 is retained in a guide ring or spider frame 30 which is rigidly retained within the cylinder and below the valve 18. A spring 31 is interposed between the frame 30 and a flange or other abutment 32 on the lower end of the threaded head 29 for holding the threaded head in position.

The upper end of the valve rod 28 is journaled in a lock nut 33 having exterior threads and screwed into the open upper end of the hollow valve stem 23, and packing material 34 and a gasket 35 are used in connection with the lock nut 36 on the valve rod for securing a water tight joint which joint however is sufficiently loose to permit relative movement of the rod 28 and the rotary valve.

In Figure 5 a spring pressed detent 37 is

indicated as carried at the underside of the flange 25 of the hollow valve stem, and this detent is designed to engage one of the depressions or sockets 38 of the bearing face 26 on the hydrant head 4.

It will be apparent from this description that with a wrench applied to the head 28' the valve rod 28 may be turned, but maintained against longitudinal movement, and that the co-action of the threaded head 29 with the threaded end of the valve stem 9 will cause the valve 7 to be unseated or seated as desired. In order to restrict flow of water to port 15 the valve is turned to bring opening 19 to register therewith, while to limit the flow of water to the port 14, the valve is turned to the right to bring opening 19 to register with port 14.

It will be noted from Fig. 2 that the rotary valve of my invention is of peculiar and novel construction, being open at the bottom to admit the water, having the pair of outlets to register with the supply outlets, and the closed top formed with the column and having the seating flange around the edge of the closed top, this form of valve serving to trap the water and direct it to the service outlets, which is of paramount importance in attaining the highest degree of efficiency.

Having thus fully described my invention what I claim as new and desire to secure by Letters Patent is—

1. In a hydrant, the combination of a casing having outlets and a valve seat, a reciprocating valve seated in the casing, a stem on the valve and a guide for the stem, a rotary valve having outlet ports for co-action with said outlets and a top to said rotary valve closing it against passage of water, a hollow stem on the rotary valve, a valve rod secured within the hollow stem and projecting below the rotary valve, a joint between the upper and lower ends respectively of the valve stem and valve rod, an annular flange on the lower end of the valve rod, a spider frame below the rotary valve, and a spring interposed between said frame and flange.

2. The combination with a hydrant having a main port and a pair of spaced auxiliary ports, of a hollow rotary valve having ports, a closed top and hollow stem, an exterior operating head for said stem, a reciprocating valve having a threaded stem, a valve rod in the hollow stem having an operating head, and a threaded socket-head on the valve rod for co-action with the threaded stem of the reciprocating valve.

3. A hydrant consisting of a base section having connection with a service supply and a valve seat in said section, a pair of superposed sections connected to said base section, one of said superposed sections being formed with a single lower outlet and a pair of upper outlets, said superposed section having a restricted portion and formed with an

annular interior shoulder, a reciprocating valve for co-action with said seat, a stem rising from said reciprocating valve, a rotary valve having an open bottom and closed at the top against passage of water, and formed with a flange seated on said shoulder, a spider frame below the rotary valve, a

valve rod having its lower portion guided in said spider frame and connected to the upper end of the valve stem, and an exterior head on said valve rod. 10

In testimony whereof I hereunto affix my signature.

ROY W. PENNY.
